UNITED STATES PATENT OFFICE.

HENRY E. REEVE, OF NEW YORK, N. Y.

LAMP-SOCKET SHELL.

1,105,305.

Specification of Letters Patent. Patented July 28, 1914.

Application filed March 9, 1911. Serial No. 613,247.

To all whom it may concern:

Be it known that I, HENRY E. REEVE, a citizen of the United States, and resident of New York, in the county of Kings and State 5 of New York, have invented certain new and useful Improvements in Lamp-Socket Shells, of which the following is a specification.

My invention relates particularly to improvements in construction by means of 10 which the parts of an incandescent lamp socket shell may be readily connected or disconnected but in which they cannot be accidentally disconnected or separated by pulling the body from the cap of the shell.

15 It is an improvement over my former Patent #980,438 dated January 3rd, 1911.

Briefly stated the improvements consist 20 in having the catches on the cap in the form of hooks for engaging the shoulders on the body so that the cap and body cannot be accidentally pulled apart and in providing a boss or projection by means of which the body of the shell may be more readily engaged for compressing and unlocking the 25 body.

Figure 1, is a front view of a lamp socket shell embodying the improvements of my invention. This shell is of the so called "key" or "pull" socket type. Fig. 2, is a 30 rear view of the same. Fig. 3, is a vertical sectional view of the shell on an enlarged scale showing the thickness of the metal somewhat exaggerated. Fig. 4, is a view of the under side of the cap portion. Fig. 5, is a 35 plan view of the body portion of the shell. Fig. 6, is a perspective view of the cap and Fig. 7 is a perspective view of the body of the shell. Figs. 8 and 9 are perspective views of the cap and body respectively of a 40 "keyless" or "switchless" socket shell of my invention.

The cap 1 and body 2 are formed of suitable material such as brass as is commonly employed. The body is provided with a 45 slot 3 which makes the upper end of the body compressible. The width of this slot is immaterial and it may be wide enough as shown in Figs. 1, 5 and 7 to accommodate the usual key or pull chain of key sockets or 50 pull sockets or a mere slit as shown at 3' in Fig. 9. The cap is provided with a flange 4 for receiving the upper end of the body and the shoulder 5 on the interior for limiting the telescopic movement of the body in 55 the cap when assembling the parts. The cap is provided with inwardly and upwardly

turned catches such as 6 and 7 formed by bending inward and upward limited portions of the edge of the cap. These catches are bent upward to a sufficient extent to 60 form hooks. The body is provided with slots having shoulders such as 8 and 9 for engaging the hook-like catches 6 and 7 respectively. The shoulder 8 is formed by perforating the metal of the body, and the 65 shoulder 9 is formed by notching the body at one side of the slot 3. To aline the parts in assembling I may also provide inter-engaging projections such as 10 and 11. In order to facilitate the assembling of the 70 parts I prefer to bend the edge of the body inwardly as at 12 and 13 adjacent the shoulder 8 and the entrance to the slot 3. As a small notch is formed at 14 in the edge of the cap below the catch 6 I prefer to provide 75 an upwardly projecting tongue 15 to fill the notch 14.

In order to disconnect the parts it is necessary to compress the upper end of the body 2 so as to clear one shoulder 8 or 9 from its 80 hook-like catch 6 or 7. To facilitate this I have provided a boss 16 serving as a thumb engaging means below shoulder 9. By this it is easy to press inwardly and upwardly when necessary on the shell adjacent the 85 shoulder 9 so as to force the shoulder 9 inwardly and disengage it from the path of the hook-like catch 7. As the catch 6 is substantially the width of the slot below shoulder 8 and the catch 7 is of such a width as 90 to extend from the left edge of the slot 3 to the right edge of the shoulder 9, the parts cannot be relatively rotated. When the projecting boss 16 is pressed inwardly and the shoulder 9 disengaged from the catch 7 the 95 body may be swung downward, at which time the catch 6 and the shoulder 8 serve as a hinge. The parts may be assembled either by direct telescopic movement or by hooking the shoulder 8 over the catch 6 and then 100 swinging the body into the cap about the catch 6 as a hinge. When the shoulder 9 slips up and out over the edge of the hook 7 it snaps against the inner wall of the flange 4 at which time the shoulders 8 and 9 are 105 securely locked above the hook-like catches 6 and 7 respectively and cannot be pulled apart.

In Figs. 8 and 9 I have shown the cap 1' and the body 2' of a so called "keyless" or 110 "switchless" socket shell. The body is rendered compressible at one or more places as

by means of cuts or slits such as 3', 3'. The hook-catches 6' and 7' are of suitable size and the body is slotted to form shoulders 8' and 9' to correspond therewith at points adjacent one or both slits 3', 3'. The edge of the body may be bent in as at 12' and 13' to form guide channels in line with the shoulders 8' and 9' to facilitate assembling. Adjacent one of the shoulders for instance 9' is 10 the boss 16' for engagement by the thumb or finger for releasing the catches. The operations of assembling and separation are substantially the same as in the key socket or pull socket type of shell. By this type of 15 hook catch the harder the pull on the body of the shell, the more securely are the parts interlocked.

What I claim is:—

1. A lamp socket shell comprising a cap 20 having limited portions of its edge bent inward and upward to form hook-like catches, a compressible body having shoulders for engaging with said hook-like catches, said body having a projecting boss adjacent one 25 of said shoulders which may be pressed to release said shoulder in order to disengage said body from said cap.

2. A lamp socket shell comprising a cap having an inwardly and upwardly project- 30 ing hook-catch and an elastic body having a slot rendering the body compressible adjacent thereto and a notch at one edge of said slot with a shoulder arranged to engage said hook-catch and a projecting boss adjacent 35 said shoulder to facilitate compressing said body and clearing said shoulder from the path of said hook-catch.

3. A socket shell comprising a tubular body and a cap having a dependent rim tele- 40 scopically engaged over the end of the body, the said cap having a locking shoulder and the body having a compressible portion pro- 45 vided with a locking shoulder adapted to engage with the locking shoulder on the cap to

prevent separation of the body and cap, and 45 the body being further provided with an out- standing boss on the said compressible por- tion disposed adjacent the rim of the cap when the parts are assembled and projecting beyond the plane of the said rim to provide 50 a thumb hold by which the compressible por- tion of the body may be pressed inwardly without interference with the rim of the cap to disengage the shoulder on the body from the shoulder on the cap and permit separa- 55 tion of the body and cap.

4. In a lamp socket shell, a compressible body having shoulders, a cap having a flange with limited portions of its edge turned in- 60 wardly and upwardly into hook-like form for engaging said shoulders, said body having a projecting boss adjacent one of said shoulders by pressure on which the body may be compressed and the adjacent shoul- 65 der lifted out of the hook-like catch with which it is engaged.

5. A lamp socket shell comprising a body slotted so as to be compressible at the upper end, a cap for receiving said body, one of 70 said members having openings affording locking shoulders and the other member hav- 75 ing hooks bent back on an incline toward the main portion of said member to provide in- clined locking shoulders in line with said shoulders when the parts are assembled so as to cause interlocking engagement when the members are relatively tensioned longi- 80 tudinally and means for alining and guiding said members so that when the end of the body is inserted in the cap in proper aline- 85 ment the parts may be pushed together and the shoulders and hooks will relatively snap past each other.

HENRY E. REEVE.
